UNITED STATES PATENT OFFICE.

ENO KANAME INONYE, OF SEATTLE, WASHINGTON.

DOOR-LATCH FOR VEHICLES.

1,161,772.

Specification of Letters Patent. Patented Nov. 23, 1915.

Application filed December 10, 1914. Serial No. 876,458.

To all whom it may concern:

Be it known that I, ENO KANAME INONYE, a subject of the Emperor of Japan, and a resident of the city of Seattle, in the county 5 of King and State of Washington, have invented certain new and useful Improvements in Door-Latches for Vehicles, of which the following is a specification.

My invention has particular reference to 10 latches for automobile doors, and its primary aim is to provide a novel latch and operating means or actuator therefor:

A further object resides in the construction and arrangement of the latch actuator 15 on the door whereby the actuator will lie within the lines of the door construction.

Those features of construction and combinations of parts on which I desire protection will be succinctly defined in the appended claims, while for a full understanding of my invention reference is to be had to the following description and the accompanying drawing wherein—

Figure 1 shows a fragmentary portion of 25 a vehicle to which my invention is applied, the latter being disclosed mostly in vertical section. Fig. 2 is a vertical transverse section thereof taken about on line 2—2 of Fig. 1. Fig. 3 is a sectional view of the actuator casing along line 3—3 of Fig. 1. Figs. 4 and 5 are detailed sections, on lines 30 4—4 and 5—5 of Fig. 1, illustrating the latch, and Fig. 6 is a fragmentary elevation of an automobile embodying my invention.

Using similar characters of reference for 35 corresponding parts throughout the several views, 1 designates the latch or bolt slidably mounted within the casing 2 for projection through casing opening 3 by spring 4, such 40 movement being confined through pin 5 of the casing operating in slot 6 of the bolt. The sliding bolt is provided with a rack 7 with which meshes a segmental gear 8 for retracting the bolt. This gear is fixed to 45 the lower end portion of a vertical rock shaft 9 which is journaled in the apertured ears 10 of casing 2. The upper portion of shaft 9 is journaled in suitable bearings of a second casing 11 and carries within the same 50 a furcated arm 12, the furcations of which are formed with alining slots 13. The outer face of casing 11 lies substantially flush with the surface of the door 14 and is provided with an opening 15 which is normally closed 55 by the latch actuator 16. Therefore, a neat

arrangement is obtained and projecting handles or parts are obviated. The latch actuator is pivoted at one end, as at 17, for swinging inwardly, the opposite end carrying an ear 18 connected to furcated arm 12 by pin 19 which slides in the slots 13 when there is relative movement between the actuator and the rock shaft. Spring 4, which is coiled about a fixed pin 20 of casing 2, has one terminal bearing against the casing 60 wall while its other terminal engages in a grooved seat 21 of the bolt 1 wherein it is retained by the abutting side wall of the casing.

In operation, to retract the bolt from 70 socket 22 to open the door, the actuator 16 is pressed inwardly to thereby rotate or rock the shaft 9. Through gear 8 and rack 7, the bolt 1 is moved inwardly. Upon releasing the actuator, spring 4 then returns the 75 associated parts to their normal position.

Although I have described, in detail, my invention, I do not intend to limit myself except as the prior art may require.

Having thus described my invention, what 80 I claim as new, and desire to secure by Letters Patent of the United States of America, is:—

1. A device of the character described comprising an upper and a lower casing, an 85 actuator plate normally held flush with the door, and pivoted by one end in the upper casing, a rock shaft extending between said casings, a rock arm secured to said shaft within the upper casing and engaging said 90 actuator plate, a latch in said lower casing, and operative connection between said latch and said rock shaft.

2. A device of the character described comprising an upper and a lower casing, an 95 actuator plate normally held flush with the door, and pivoted by one end in the upper casing, a lug upon the inner side of said plate at its other end, a rock shaft extending between said casings, a rock arm secured 100 upon said shaft within the upper casing, and engaging the actuator plate, guiding engagement between said lug upon the plate and said rock arm, a latch in the lower casing, and operative connection between said 105 latch and said rock shaft.

3. A device of the character described comprising an upper and a lower casing, an actuator plate normally held flush with the door and adapted to be depressed, said 110

plate being pivoted by one end in the upper casing, a lug upon the inner side of said plate at its other end, a pin in said lug, a rock shaft extending between said casings, a rock arm secured upon said shaft within the upper casing, said rock arm having a cam surface engaging the actuator plate and a slot for guiding engagement with said pin, a latch in said lower casing, and opera-

tive connection between said latch and said rock shaft.

Signed at Seattle, Washington this 24 day of November 1914.

ENO KANAME INONYE.
